UNITED STATES PATENT OFFICE.

HENRY T. SPRING AND CHARLES A. SPRING, OF ROYER'S FORD, PENNSYLVANIA, ASSIGNORS TO THE BUCKWALTER STOVE COMPANY, OF SAME PLACE.

DESIGN FOR A RANGE AND BOILER.

SPECIFICATION forming part of Design No. 20,437, dated December 23, 1890.

Application filed November 24, 1890. Serial No. 372,558. Term of patent 3½ years.

To all whom it may concern:

Be it known that we, HENRY T. SPRING and CHARLES A. SPRING, citizens of the United States, residing at Royer's Ford, in the county 5 of Montgomery, State of Pennsylvania, have invented and produced a new and original Design for a Range and Boiler, of which the following is a specification, reference being had to the accompanying photograph, forming 10 part thereof.

The leading features of our design for a range and boiler are as follows: the body of the range with paneled sides and doors, the open-scroll panels aside of the ash-pit door, the 15 open-work of the standards of the boiler, and the saddle for the boiler with circular ends, a circular front, and parallel bars on said front.

In the photograph, A designates a range and boiler embodying the features of our design, which consist of the range-body 1, with 20 paneled sides 2, doors 3, and open-scroll panels 4, the open-work standards 5, the saddle 6, with circular ends 7, circular front 8, and parallel bars 9 on said front.

We claim—

A design for a range and boiler, as shown 25 and described.

HENRY T. SPRING.
CHARLES A. SPRING.
